UNITED STATES PATENT OFFICE

137,183

DESIGN FOR AN APRON

Helene Pons, New York, N. Y.

Application November 29, 1943, Serial No. 111,808

Term of patent 3½ years

To all whom it may concern:

Be it known that I, Helene Pons, a citizen of the United States, residing at New York city, in the county and State of New York, have invented a new, original, and ornamental Design for an Apron, of which the following is a specification; reference being had to the accompanying drawing, forming a part thereof.

Fig. 1 is a front view of an apron, showing my new design.

Fig. 2 is a rear view of the same.

Fig. 3 is a cross-section taken through line 3—3 of Fig. 2, to show the appearance of the pleat and the pocket.

The dominant feature of the design resides in the portions shown in full lines.

I claim:

The ornamental design for an apron, substantially as shown and described.

HELENE PONS.
